OIL WELL PUMPING AND FLOWING APPARATUS

Filed Sept. 11, 1930

UNITED STATES PATENT OFFICE

ROBERT E. BERWICK, OF NEWKIRK, OKLAHOMA

OIL WELL PUMPING AND FLOWING APPARATUS

Application filed September 11, 1930. Serial No. 481,242.

This invention relates to oil well flowing and pumping apparatus, and has for one of its objects to conserve and equalize the amount of gas pressure necessary to elevate 5 the column of liquid in the tubing.

The invention has for a further object to cut down and conserve the lifting power of the pumping valve.

The invention has for a still further object 10 to reduce to the minimum the overhead expense incident to the elevation of oil from wells which expense consists mainly of the pulling of tubing and rods from the well.

To attain the foregoing and other objects, 15 the nature of which will appear as the description proceeds, the invention comprehends the provision of a valve which shall be adapted to permit pressure fluid in the casing to flow into the tubing when the pressure in the latter falls below that in the former and which shall be adapted to prevent the fluid in the tubing from flowing into the casing and when the pressure of the former falls below that in the latter.

20 The invention consists in the construction, combination and arrangement of parts hereinafter fully described and claimed, and illustrated in the accompanying drawings, wherein:—

25 Figure 1 is a vertical sectional view illustrating the application of the valve to the tubing of an oil well flowing or pumping apparatus;

Figure 2 is a sectional view taken on the 30 horizontal plane indicated by the line 2—2 of Figure 1, and

Figure 3 is a view in side elevation of one of the stems of the valve.

Referring in detail to the drawings, 1 designates a fragmentary portion of the tubing 35 of an oil well flowing or pumping apparatus, and 2 designates the valve.

The valve 2 comprises a one piece body 3 which is of hollow cylindrical formation and 40 is internally screw threaded to receive the adjacent ends of adjacent sections 4 of the tubing 1. The body 2 is provided in its inner side and centrally between its ends with an annular groove 5, the depth of which is less 45 than the thickness of the wall of the body, and

which gradually increases in width in the direction of the longitudinal axis of the body. The body 2 is provided with a plurality of vertical chambers or passages 6 which extend from a plane located above the bottom of the groove 5 to and through the lower end of the body. The passages 6 communicate near their upper ends with the bottom of the groove 5 by way of radial ports 7 which are smaller diametrically than the greatest width 55 of the groove. Cylindrical stems 8 are arranged vertically in the passages 6 and extend from the lower ends of the passages to a point short of the port 7. The stems 8 are carried by plugs 9 which are located at the 60 lower ends of the stems and are screw threaded engaged, as at 10, with the lateral walls of the passages 6. The plugs 9 are provided in their lower sides with notches 11 to permit the stems 8 to be applied to or removed from the passages 6 by a screw driver. The stems 8 and their attaching plugs 9 are provided with passages 12 which extend longitudinally therethrough and have their upper ends enlarged to provide seats 13 for ball valves 14. 65 Those portions of the passages 6 located above the stems 8 constitute chambers for the valves 14, and these chambers are of sufficient height to permit the valves to be moved up off their seats 13. 70

The stems 8 are located laterally beyond the tubing 1, and in view thereof, the lower ends of their passages 12 are in communication with the casing of the well. When the pressure in the tubing 1 is greater than that in the casing of the well, the valves 14 are seated 75 and prevent the fluid in the tubing from flowing into the casing. When the pressure in the casing becomes greater than the pressure in the tubing, the gas or air in the casing flows 80 upwardly through the stems 8 past the valves 14 and into the groove 5 and enters the column of liquid in the tubing 1 with the result that the lifting impulse is imparted to the column of liquid. As the groove 5 is annular, the air or gas flowing thereinto from the casing will be evenly distributed into the column 85 of fluid in the tubing. The valve may be provided with any number of ports 7 and the 90

means for controlling the flow of gas or air in the casing thereinto.

From the foregoing description, taken in connection with the accompanying drawings, it will be apparent that I have provided a flow valve for the tubing of an oil well flowing or oil well pumping apparatus which is adapted, when the pressure in the casing is greater than that in the tube, to permit gas or air in the casing to flow into the tubing and thus impart a lifting impulse to the column of liquid in the tubing.

While I have described the principle of the invention, together with the structure which 15 I now consider the preferred embodiment thereof, it is to be understood that the structure shown is merely illustrative and that such changes may be made, when desired, as fall within the scope of the invention as 20 claimed.

I claim:—

A flow valve for the tubing of an oil well flowing and pumping apparatus, comprising a one-piece hollow body adapted to be interposed in the tubing and provided in the inner side of its wall between the ends thereof with an inner annular groove of less depth than the thickness of the wall and increasing in width in the direction of the longitudinal 25 axis of the body, the body being provided in its wall radially beyond the bottom of said groove with a passage extending from the lower end of the wall to a point above the bottom of the groove, the wall of the body being 30 provided with a radial port smaller diametrically than the greatest width of the groove and establishing communication between the upper end of the passage and the bottom of the groove, and a downwardly seat- 35 40 ing valve in the passage.

In testimony whereof I hereunto affix my signature.

ROBERT E. BERWICK.
